UNITED STATES PATENT OFFICE.

ROBERT BURGESS, OF NEWTON CENTER, MASSACHUSETTS, ASSIGNOR OF ONE-HALF TO
JOSEPH H. JONES, OF WINTHROP, MASSACHUSETTS.

BOBBIN.

Application filed March 11, 1922. Serial No. 542,834.

To all whom it may concern:

Be it known that I, ROBERT BURGESS, a citizen of the United States, residing at Newton Center, in the county of Middlesex, 5 State of Massachusetts, have invented a certain new and useful Improvement in Bobbins, of which the following is a specification, reference being had therein to the accompanying drawings.

10 The invention is designed for application chiefly in the case of bobbins employed in spinning, twisting, and the like. It provides improved means for securing frictional or adhesive driving engagement between a bobbin and the spindle upon which it is mounted, whereby to ensure rotation of the bobbin and spindle in unison. Such means, specifically stated, comprises an annulus of compressed cork interiorly disposed within a 15 bobbin, and adapted to encircle the blade or stem of a spindle upon which the bobbin is placed and to engage with the said blade effectively for the purpose stated. The invention further provides in connection with 20 a bobbin a spindle-blade engaging unit comprising a container-shell and an annulus of frictional or adhesive material, preferably compressed cork, held within the said container-shell and protected thereby. The invention provides further a bobbin of plastic 25 material molded over and around a spindle-blade engaging unit or annulus.

In the drawings:—

Fig. 1 shows a spindle and certain associated parts, with a bobbin having an illustrative embodiment of my invention applied to said spindle, the bobbin being partly in section to show the frictional or adhesive spindle-blade engaging means.

40 Figs. 2, 3, and 4 are respectively an elevation, a plan, and a sectional view of the spindle-blade engaging unit of Fig. 1.

Fig. 5 shows, partly in section, a bobbin of slightly modified character.

45 Having reference to the drawings:—

The body of each of the bobbins 1 and 11 shown in Figs. 1 and 5 is composed of plastic material, and is most advantageously formed into the desired shape by moulding, 50 though it may also be made by machining a solid body of such material into shape. In practice I employ preferably the substance known as "bakelite." As shown, each of the said bobbins has, as usual, at a point α near 55 the top thereof an internal constriction or

shoulder 4 to form a bearing which fits the tip of the blade of the spindle to which the bobbin is applied.

Each of the bobbins shown in the drawings has combined therewith adjacent the 60 internal bearing 4, a spindle-engaging unit comprising a rigid cylindrical shell or container 3, otherwise the container-shell aforesaid, and the annulus 5, of frictional or adhesive material, confined within said shell 65 or container. The shell or container 3 is preferably of metal. It is annular, to permit a spindle-blade to extend through it and the annulus 5 within it. In the manufacture of a bobbin having the body thereof 70 formed of plastic material, the said unit is combined with the bobbin body ordinarily by being placed in the mould so as to become firmly embedded in the mass of plastic material in its permanent position 75 concentric with the bore of the bobbin. Proper centering of the unit within the mould is secured by means of a pin or the like occupying the central passage through the unit. The container-shell serves in the case of an annulus of compressed material such as cork 80 to keep the material in compressed state, and prevents loss of shape, etc., of the annulus during the filling of the mould or by reason of the compression to which the contents of the mould 85 are subjected in the moulding process. The plastic material may be caused to extend inward somewhat at the under side of the container-shell, as in Fig. 1, or this feature may be omitted, as in the 90 case of the bobbin shown in Fig. 5. In the present instance, in order to insure positive anchoring of the unit in place within the bobbin, the container-shell is formed with swamped sides, that is, with a groove or depression running around it circumferentially. This groove fills with the plastic material, which firmly locks the unit in place. The same result may be provided for in practice in other well-known ways. In the 95 case of bobbins which are turned down and shaped in the solid state by tool work, the container-shell and the seat therefor within the bobbin are prepared so that the container-shell shall fit tightly within the said 100 seat, and the former is driven home into its final position so that it remains fixed thereby by friction. In such case the swamped sides or grooving are unnecessary.

The frictional material 5 for securing the 110

desired adhesive engagement between bobbin and spindle preferably is cork, which is the most satisfactory substance that I have found thus far for this purpose, and I prefer that the cork shall be in a compressed state, for compressed cork has greater wearing qualities and also greater gripping powers due to its greater density.

In some cases, other suitable yielding or elastic frictional material may be employed in the place of cork.

The container or shell 3 is formed, as shown best in Figs. 1 and 4, with inturned flanges 3^a, 3^b, at the top and bottom, respectively, thereof to confine the frictional or adhesive material against displacement vertically. The lower flange, 3^b, also serves to protect the said material from being injured or torn by the tip of the spindle. The said lower flange also is formed concave, to center the spindle tip with the bore of the container or shell in donning the bobbin upon a spindle, and thereby facilitate speedy application of the bobbin to the spindle.

In the manufacture of the illustrated spindle-blade engaging unit, the cork 5, or other material used instead thereof, is placed within the container-shell before the top flange, 3^a, has been bent down. In volume the cork or other material will exceed the capacity of the container-shell. It is compressed into the latter and the top flange 3^a is pressed down into place.

It will be clear from the foregoing description that in some cases the principles of my invention may be applied with considerable variation in the form, materials and method of combining, and to other forms of bobbins, without departing from the scope of my invention. In some cases, also, an annulus of compressed cork, or the described spindle-blade engaging unit comprising such an annulus and a container-shell, as 3, may be introduced into the bore of a bobbin made of wood.

I claim as my invention,—

1. A bobbin comprising a body of plastic material, a cylindrical container-shell em-

bedded in said body, and a spindle-blade-engaging cork annulus contained within 50 said container-shell.

2. A bobbin comprising a body formed of plastic material, a cylindrical container embedded in said body, and a spindle-blade-engaging annulus of compressed cork confined within said container. 55

3. A bobbin comprising a body formed of plastic material, a cylindrical container fixed within said body, and an annulus of elastic frictionally adhesive material within said 60 container.

4. A bobbin formed of bakelite having embedded therein a container, and a spindle-blade-engaging annulus of compressed cork confined within said container. 65

5. A bobbin formed of plastic material and having a bearing comprising a constriction or shoulder in the bore of said bobbin adapted to fit a spindle-blade, a cylindrical container adjacent said constriction or shoulder, and an annulus within said container of material adapted to engage frictionally with the blade of a spindle on which the bobbin is mounted. 70

6. The combination with a spinning bobbin or the like, of a spindle-blade engaging unit within said bobbin comprising an annulus of frictional or adhesive material, and a container-shell enclosing said annulus. 75

7. A spinning bobbin or the like having 80 concentrically disposed therein a spindle-blade engaging annulus composed of compressed cork.

8. A spinning bobbin or the like having combined with the body thereof an internally-located spindle-blade engaging unit comprising a container-shell and an annulus of compressed cork confined within said container-shell. 85

In testimony whereof I affix my signature 90 in presence of two witnesses.

ROBERT BURGESS.
